UNITED STATES PATENT OFFICE.

ROBERT SANFORD RILEY, OF WORCESTER, MASSACHUSETTS, ASSIGNOR TO SANFORD RILEY STOKER CO. LTD., OF WORCESTER, MASSACHUSETTS, A CORPORATION OF MASSACHUSETTS.

COAL-AGITATOR FOR MECHANICAL STOKERS.

1,208,011.

Specification of Letters Patent. Patented Dec. 12, 1916.

Application filed March 4, 1916. Serial No. 82,239.

To all whom it may concern:

Be it known that I, ROBERT SANFORD RILEY, a citizen of the United States, residing at Worcester, in the county of Worcester and State of Massachusetts, have invented a new and useful Coal-Agitator for Mechanical Stokers, of which the following is a specification.

This invention relates to a device for agitating coal in a mechanical stoker of that type in which the coal is fed from a hopper by means of reciprocating plungers.

The principal objects of the invention are to provide an agitator of exceedingly simple form which will operate in such a way as to break up effectually any arch of coal that may form in the hopper and cause it to fall down at the end of the plunger at the particular time when the latter is withdrawn; to provide a construction in which the agitator cannot act at a time when the plunger is about to make or making its charging stroke, thus providing for a maximum efficiency; and also to provide a construction in which the entire agitator is located within the hopper and is actuated by the charging plunger itself in the hopper so that there will be no necessity of connecting it up from the outside.

Reference is to be had to the accompanying drawings, in which—

Figure 1 is a central sectional view of a section of a hopper of a mechanical stoker with a preferred embodiment of this invention applied thereto; Fig. 2 is a similar view showing the parts in the other extreme position, and Fig. 3 is an elevation of the same looking at the end of the plungers, the bottom of the hopper appearing in section.

When coal is moist or otherwise of a caking nature, it tends to form arches in the hopper of a mechanical stoker, and thus prevent the uniform and continuous feed of the coal. Several devices have been designed for preventing this, but so far as I am aware they have been worked from the outside and also it has often been the case that they have been caused to operate independently of the position and direction of motion of the several plungers. Consequently whenever the agitator was working it might tend to force coal toward some plunger that was making its working stroke. This tended to clog the device and was any-

thing but efficient. By my invention these difficulties are avoided by the substitution of an extremely simple device which works efficiently in practice.

Referring particularly to the drawings it will be seen that the invention is shown as applied to a well-known type of stoker in which the coal is fed from the bottom of a hopper 10 by means of a series of reciprocating plungers 11. According to my invention each plunger is provided with a separate agitator 14 which works with that plunger irrespective of the other plungers and operates at the right time with reference to its own plunger. In this case the extension 12 with which each plunger is provided has a notch 13 in its top to which is pivoted an agitator hook 14. This hook extends upwardly from the forward end of the plunger therefore and is provided with a nose 15 arranged almost at right angles to the body 75 of the hook or agitator. The agitator is made with its lower edge near the pivot thin so as to cause the least possible resistance when it is forced through the coal. At its upper end are cross rods 16 made of sufficient length to reach practically between the adjacent plungers and prevent arching in the space not touched by the narrow hook.

From this it will be seen that the lower end of the agitator hook reciprocates with the plunger while the upper end is free to stand in any position depending upon the condition of the coal it encounters. It is capable of moving clear across the hopper as the plunger operates. It will be noted that during the forward or working motion of the plunger the agitator has a tendency to fall back to the position shown in Fig. 2 and it is during the reverse stroke that it has a tendency to move forward toward the position shown in Fig. 1. Its operation is synchronous with that of the plunger and tends to bring the coal down to the front of the plunger as the plunger is being withdrawn and while there is a space in the front of the plunger for receiving it. Furthermore the space below the two bars 16, when the hook is in its highest position, holds enough coal to fill the space in front of the plunger, that is, a full charge.

The agitator also has another function in that when in the position shown in Fig. 1 while the plunger is about to move for-

ward, it prevents an excessive charge of coal packing into the space in front of the plunger and tends to take part of the pressure off that which is located there. The 5 agitator, by its up and down motion, breaks up the arch of coal formed in the hopper above the plunger at exactly the proper time so that it can not assist the natural tendency of the coal to pack at that point and tend 10 to resist the action of the plunger. Furthermore, by having a separate agitator for each plunger necessarily operating synchronously therewith there is no possibility of having the agitator, while efficient for one 15 plunger, reduce the efficiency of another as has been the case with some of the devices heretofore suggested. Furthermore, in case of the presence of a hard lump of coal in the way of the agitator it does not bring any 20 exceptional strain upon the operating parts of the plunger because the agitator is capable of swinging freely on its pivot.

It will be understood that the cylinder and throat of the hopper in which the plunger 25 works should be designed to have sufficient clearance to allow the agitator to move into the two extreme positions shown.

Although I have illustrated and described only a single form of the invention and 30 shown it as applied only to one type of stoker hopper I am aware of the fact that modifications can be made therein by any person skilled in the art and that it can be applied to other types of hoppers without 35 departing from the scope of the invention, as expressed in the claims. Therefore, I do not wish to be limited to all the details of construction herein shown and described, but

40 What I do claim is—

1. In a coal feeding mechanism, the combination with a hopper, of a rigid coal agitator located within the hopper, and means

located in the hopper for operating one end of said agitator, the other end also being 45 movable back and forth in the hopper.

2. In a coal feeding mechanism, the combination with a hopper and a plunger for feeding coal therefrom, of an agitator in the hopper connected to be operated by the 50 plunger and having one end movable freely in the hopper.

3. In a coal feeding mechanism, the combination with a hopper and a reciprocating plunger at the bottom thereof, of a coal agitator pivotally connected with the end of the plunger and extending upwardly therefrom in the hopper the upwardly extending part being free in the hopper.

4. In a coal feeding mechanism, the combination with a hopper and a reciprocating plunger, of a coal agitator pivotally connected with the end of the plunger and located in the hopper, and having a nose extending at an angle therefrom forwardly. 60 65

5. In a coal feeding mechanism, the combination with a hopper and a reciprocating plunger at the bottom thereof, of a coal agitator pivotally connected with the end of the plunger and extending upwardly therefrom in the hopper, said agitator having a nose substantially at right angles thereto, and constructed and arranged to provide a space underneath said nose when the plunger is retracted sufficient to hold a complete 70 75 charge of fuel.

6. In a coal feeding mechanism, the combination with a hopper and a reciprocating plunger, of a coal agitator pivotally connected with the end of the plunger in the 80 hopper and provided with cross rods near the free end thereof.

In testimony whereof I have hereunto set my hand.

ROBERT SANFORD RILEY.
